CLAIM

The ornamental design for a candy dispenser bin with reflective back surface, as shown and described.

DESCRIPTION

FIG. 1 is a perspective view of a candy display bin with reflective back surface showing my new design;

FIG. 2 is a front elevation view thereof;

FIG. 3 is a rear elevation view;

FIG. 4 is a left side elevation view, a right side elevational view being a mirror image;

FIG. 5 is a top plan view showing my new design; and,

FIG. 6 is a bottom plan view.
